UNITED STATES PATENT OFFICE.

EDWARD C. LAWRENCE, OF KANSAS CITY, MISSOURI.

DISPLAY STAND.

1,406,464.

Specification of Letters Patent. Patented Feb. 14, 1922.

Application filed February 10, 1921. Serial No. 444,007.

To all whom it may concern:

Be it known that I, EDWARD C. LAWRENCE, a citizen of the United States, residing at Kansas City, in the county of Jackson and State of Missouri, have invented certain new and useful Improvements in Display Stands; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to an article display stand and the primary object is to provide an adjustable stand particularly for use in supporting display cards or signs.

Heretofore it has generally been the practice to provide a different size frame for each different size display card, thus requiring an unnecessarily large stock of display stands to be maintained on hand at all times.

With my invention I can provide a standard type and size of display stand which will be adjustable to suit varying conditions. For example, a display card of relatively small area may be efficiently and artistically supported by the stand and when it is desired to enlarge the advertising space by providing a larger card, the display stand can be adjusted to meet this requirement.

Various general arrangements may be provided while still conforming to the generic principles involved and I, therefore, reserve the right to make such changes in form, proportion and minor details of construction as come within the scope of the appended claim.

In the drawings,

Fig. 1 is a perspective view of a stand constructed in accordance with my invention, the display card being shown in dotted lines.

Fig. 2 is a vertical, longitudinal, sectional view through the stand, the base, and a display card in place, the adjustable bar or rod for the standard being shown in elevation.

Fig. 3 is a perspective view of a modified form of stand, and

Fig. 4 is a further modified form of an upper jaw and a light reflector.

Referring now to the drawings by numerals of reference:

1 designates a base on which is a hollow standard 2. The standard 2 may be fas-

tened to the base by fastening devices shown as screws 3. There is a rigid jaw 4 extending laterally from the standard 2 having a horizontal card-edge-receiving groove 5 into which the bottom of the card 6 may be received. The jaw 4 is preferably of sufficient area to provide an extended surface 7, which may be utilized as a stand for the display of goods if desired.

Slidable within the hollow standard 2 is a rod or bar 8, polygonal in cross section, received within the polygonal opening 9 so that the bar will be guided in the opening 9 but be prevented from turning.

At the upper end of the bar or rod 8 is a movable jaw 10, rigid with the bar 8 but movable with respect to the jaw 4. The forward lower face of the jaw 10 is provided with a lateral groove 11, co-operating with the groove 5 to support the card 6, as shown in Fig. 2. The head 10 may be fastened to the bar by fastening devices such as nails 12.

When the device shown in Fig. 2 is in the position shown in Fig. 1, the smaller size card will be supported, the jaw 10 at that time resting upon or substantially resting upon the upper edge of the standard 2. If it is desired to enlarge the advertising space by utilizing a larger card, the rod 8 will be raised. For example, by engaging the head 13 so that the jaw 10 may be moved away from the jaw 4 a sufficient distance to accommodate the larger card; then the jaw 10 will be lowered until the upper edge of the card is received within the groove 11 so that the card will be held in the position shown in Fig. 2. The upper edge of the card then serves as a rest or support for the jaw 10, insuring that the two jaws 4 and 10 will securely hold the card.

Therefore, it will be seen that the jaws 4 and 10 are movable toward and away one from the other so that they may have relative adjustments to accommodate cards of any size between two extremes. Therefore, a single standard type of display stand will accommodate a number of sizes of cards.

In Fig. 3 I have shown a slightly modified form in which the standard 14 is supported upon a base 15. The hollow standard 14 receives a vertical adjustable bar or rod 16 provided with a groove 17, into which projects one end of a pin 18, passing through the standard 14 so that the bar or rod 16 may have vertical movement but be held against rotative movement. On the

standard 14 is a rigid jaw 19, corresponding to the jaw 4 on the standard 2. The rod or bar 16 carries a movable jaw 20 corresponding to the jaw 10.

5 The jaws 19 and 20 are provided with card-edge-receiving grooves 21 and 22 and since the jaw 20 is vertically adjustable with respect to the jaw 19, it is obvious that the display stand shown in Fig. 3 is also capable of receiving cards of different size.

10 In Fig. 4 I have shown a further modified form in which the jaw 20' is provided with a forward extension in the form of a concave or trough-like portion 22, preferably provided with a reflector surface 23 and within which is a light-emitting medium 24 adapted to cast its rays down upon the front surface of the card.

15 The light source 24 is shown as a lamp of special construction, the filaments of which are elongated within an elongated globe and the filaments of which are preferably energized through a conductor 25, which passes through the hollow rod 26, fastened to the 20 jaw 20'.

If it is desired to utilize the stand as a display device, the card may be omitted and the articles may be placed upon the surface 7 in Fig. 1 or on the surface 27 in Fig. 3. It will be obvious, however, that the device 30 is particularly applicable for use as a card display stand and that the jaws have relative movement with respect to one another so that various size cards may be readily accommodated.

35 What I claim and desire to secure by Letters-Patent is:

A display stand comprising a standard, a jaw rigid on the standard, a second jaw adjustably supported by the standard and having movement toward and away from the first jaw, off-set grooves in said jaws to receive a card whereby the card will be held at an angle with respect to the standard, and a light-reflecting hood having a light 40 source for directing the rays of light in the direction of the card held between the jaws.

45 In testimony whereof I affix my signature.

EDWARD C. LAWRENCE.
